By his atty
UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,945, dated June 24, 1890.

Application filed April 15, 1890. Serial No. 348,102. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawings, forming part thereof.

10 In the drawings, Figure 1 is a side elevation of a cane or umbrella handle illustrating my new design, and Fig. 2 is a cross-section of same on line *x x*.

15 A is the body part, and extends up vertically for a short distance and then is formed into a large loop B. The vertical or lower portion of the body is encircled by depressed spirals C and ornamental spirals D, which are plain. The bottom of the body is finished by 20 an annular plain band E. The loop B is made

approximately diamond-shaped in cross-section, as indicated in Fig. 2, and is relieved by highly ornamental work representing a feather. The extreme end of the loop B is like a foot F and rests upon the upper portion of 25 the body part A.

The handle is made of any suitable material.

Having now described my new design, what I claim as new, and desire to secure by Letters Patent, is—

The design for cane or umbrella handles, substantially as herein described and shown.

In testimony of which invention I have hereunto set my hand.

HENRY O. SCHMIDT.
